UNITED STATES PATENT OFFICE

ARNOLD EGLI, OF HAMBURG, GERMANY

BEARING ARRANGEMENT FOR MULTICOLOR PRINTING MACHINES

Application filed May 18, 1929, Serial No. 364,267, and in Germany May 19, 1928.

In multi-color sheet intaglio printing machines it is necessary that the printing cylinders, of which preferably several are arranged on the periphery of a common impression cylinder, be set accurately towards each other not only in a radial direction but also in an axial sense and in such a manner, that when the setting is finished the printing cylinder can be moved close to the impression cylinder and away from it without impairing the setting. Said printing cylinder must be supported thereby so it can absorb any radial pressure.

In accordance with the present invention, each printing cylinder is supported by three bearings, two of which are adapted to absorb only radial pressures, whereas they permit axial shifting of the printing cylinder. These bearings are arranged in the engine frame by which the impression cylinder also is supported. I provide the third bearing in a third partition in the engine structure, such bearing being arranged to secure the printing cylinder against axial shifting during the operation, but permitting an advanced setting in this direction, said bearing being constructed in such a way that it can absorb only radial forces in a perpendicular direction.

One embodiment of said invention is represented in the accompanying drawings, wherein for the sake of a better understanding only those engine parts have been shown which are directly affected by the present invention, while the well known parts of the multi color sheet intaglio printing machine necessary for its operation as for instance the driving gear of the printing cylinder and the like have not been illustrated. In said drawings,

Fig. 1 is a longitudinal section, partly in elevation, of my improved printing cylinder bearing.

Fig. 2 is a side elevation of a bearing bracket on line II—II of Fig. 1.

Fig. 3 illustrates in side view a detail of the driving gear of the printing cylinder.

Fig. 4 is a section on line IV—IV of Fig. 1.

Fig. 5 shows a section through the impression cylinder and the printing cylinders of

a three color sheet intaglio printing machine.

It has been found suitable to use in multi-color sheet intaglio printing machines tubular printing cylinders removably arranged on the supporting elements so that they can be readily exchanged. A tubular printing cylinder 10 of this type, ribbed on the inside, is shown in the embodiment of the invention illustrated. The cylinder is mounted between the tightening devices 5, 6 and the setting devices 7, 8 and 9 on a conical supporting member 2 rigidly attached to the shaft 1. The shaft 1 of the printing cylinder is supported in three bearings, two being located in the two main walls *a*, *b* of the engine frame, and the third in a special partition *c* of the engine frame arranged outside the two walls *a*, *b*. The bearings in the engine walls *a*, *b* are arranged as shown in side view in Fig. 2 and comprise bearing brackets 11, 11', mounted to swing around the bolts 12, 12', said brackets being provided with conical bores for receiving conical bearing cases 13, 13' and cross bearings 14, 14'. The latter are mounted on sliding bearing sleeves 15, 15' which cannot turn around the shaft ends but may be shifted longitudinally on the shaft. It will be seen that these bearings arranged in the walls *a* and *b* can absorb radial pressures when the bearing brackets 11, 11' have been placed into the pressure position by means of the bell crank lever *k* (Fig. 2) and when said printing cylinder is operating together with the impression cylinder.

The driving of the printing cylinder is effected by a driving wheel, not shown in the drawings, engaging the toothed wheel 16, which turns freely on shaft 1. The toothed wheel is provided on the periphery of the rim with a groove 16' engaging the guide finger 17 attached to the bearing case; said finger preventing an axial shifting of the wheel against the engine frame *b*. The shaft is turned by the toothed wheel with the aid of a disk 18 (Fig. 3) which can be fixedly clamped upon the shaft end, a slot 19 in said disk engaging a catch bolt 20 of the wheel 16, the connection between the slot 19 and the catch bolt 20 being made by a wire 21.

19 and the bolt 20 being effected by an adjustable eccentric sleeve 21 and a sliding hub 22. It is possible by these means to set the shaft 1 and the printing cylinder 10 in radial direction with regard to the peripheral direction, the rough setting being effected by turning and tightening the clamping disk 18, whereas the fine setting is done by a turn of the eccentric sleeve in the hub 22. The axial shifting of the shaft in the limits which are to be considered here is not obstructed by this connection as the hub 22 may be shifted axially in the slot 19.

The setting in an axial sense is done by means of a hand wheel 23, which turns on the outer shaft end, but is arranged so that it cannot be shifted axially; the hub of said wheel being provided with threads 23' on the external periphery engaging with the internal threads in the sleeve 25. This sleeve 25 with its flange rings 25' and 25'' is placed against the partition *c* of the engine frame by a tight fit thus preventing any shifting in axial direction. While said sleeve generally is not guided axially in the wall its upper side is provided with a flattened portion 28, which may be placed against a corresponding surface in the partition *c*. A pin 30 arranged in the wall *c* engages with a slot 29 to prevent a turning of the threaded sleeve 25. The setting of the shaft 1 together with the parts mounted thereon can therefore be effected in axial direction in any desired way by turning the hand wheel 23. When the setting has been effected the slotted and threaded sleeve 25 is clamped tightly upon the spindle 23 so that the setting becomes fixed. If the printing cylinder 10 is to be removed, this will be effected by means of the flattened surface 28, and it is only necessary for this purpose to take out the bearing case 13' (Fig. 1 on the right) whose smallest diameter is greater than the greatest outside diameter of the printing cylinder 10 and of the tightening device 5. When the bearing case 13' with the bearing 14' has been taken out, the surface 28 will be placed close to the casing wall *c* securely supporting in nearly horizontal position the shaft 1 together with the bearing 13, 14 in the wall *b*.

By means of the improved mechanism above described, the shaft 1 can be axially shifted to adjust the printing cylinder or shell 10, which is usually of copper, accurately with respect to the printing cylinders on the other printing rollers of the machine. Because of the fact that the driving gear 16 is loose on the shaft 1, it can remain constantly in mesh with its driving pinion (not shown) irrespective of the axial shifting of such shaft. Motion is therefore transmitted from the gear wheel 16 to the shaft 1 in an indirect manner with the aid of the bolt 20, sleeve 21 and sliding hub 22 and disc 18, the

latter being keyed to the shaft. Axial movement of the wheel 16 with the shaft 1, which may occur when the wheel becomes stuck or frozen to the shaft, is prevented by the finger 17 which may be positioned on a fixed part of the machine and engages a groove 16' on the wheel.

My improved arrangement of bearings allows the resetting of the printing cylinder into the original position to take place in a quick manner without play by means of the conical bearing case; a bearing case of cylindrical or rectangular shape necessitating much play for the easy exchanging or replacement of the cylinder on account of the edging, the eliminating of which would be accompanied by difficulties of design.

I claim:

1. Multi color sheet intaglio printing machine comprising, in combination, an impression cylinder, printing cylinders movable towards the impression cylinder and away from it, each printing cylinder supported by a shaft, at least two bearings for supporting the shaft, a third bearing, and stops on the shaft at or next to the third bearing and adapted to secure the shaft against axial shifting.

2. Multi color sheet intaglio printing machine comprising, in combination, an impression cylinder, printing cylinders movable towards the impression cylinder and away from it, each printing cylinder supported by a shaft, at least two bearings for supporting the shaft, a third bearing, stops on the shaft at or next to the third bearing, and means for fixing said third bearing after its setting against the machine frame.

3. Multi color sheet intaglio printing machine comprising, in combination, an impression cylinder, printing cylinders movable towards the impression cylinder and away from it, each printing cylinder supported by a shaft, at least two bearings for supporting the shaft, bearing brackets on the two main walls of the frame of the machine for supporting the two first bearings, a third bearing for said shaft, stops on the shaft at or next to the third bearing, and means for supporting said third bearing.

4. Multi color sheet intaglio printing machine comprising, in combination, an impression cylinder, printing cylinders movable towards the impression cylinder and away from it, each printing cylinder supported by a shaft, at least two bearings for supporting the shaft, bearing brackets on the two main walls of the frame of the machine for supporting the two first bearings, a third bearing, the machine frame having also a third wall, a hand wheel having a hub on the end of the printing cylinder shaft, stops on said shaft on both sides of the hub of the hand wheel, threads on the hub of said hand wheel, a threaded bearing element receiving said

- hub, said bearing element arranged in the third frame wall, means for securing said element in the frame wall against turning and shifting; said bearing element provided with a slot on the front face, and means for forcing the walls of said slot toward each other to fix the hub of the hand wheel after the setting of same with respect to the machine frame.
- 10 5. Multi color sheet intaglio printing machine comprising, in combination, an impression cylinder, printing cylinders movable towards the impression cylinder and away from it, each printing cylinder supported by a shaft, at least two bearings for lodging the shaft, bearing brackets on the two main walls of the engine frame of the machine for supporting the two first bearings, a third bearing, the machine frame having also a third wall, a hand wheel having a hub on the end of the printing cylinder shaft, stops on said shaft on both sides of the hub of the hand wheel, threads on the hub of said hand wheel, a threaded bearing element receiving said hub, said bearing element arranged in the third frame wall, means for securing said bearing element in the frame wall against turning and shifting; said bearing element provided with a slot on the front face, and means for forcing the walls of said slot toward each other to fix the hub of the hand wheel after the setting of same with respect to the machine frame. the upper part of said bearing element being flattened, such flattened portion adapted to support the shaft after the removal of one of the two other bearings.
- 15 6. Multi color sheet intaglio printing machine comprising, in combination, an impression cylinder, printing cylinders movable towards the impression cylinder and away from it, each printing cylinder supported by a shaft, at least two bearings for supporting the shaft, a third bearing, stops on the shaft at or next to the third bearing, a driving wheel on the shaft of the printing cylinder, a finger rigidly connected with the machine frame, a groove in said wheel engaged by said finger, a catch on said wheel, a sleeve around said catch, a second sleeve around said first sleeve, and a driven wheel rigidly connected with the printing cylinder shaft, said driven wheel having a radial slot for receiving the second sleeve.
- 20 7. Multi color sheet intaglio printing machine comprising, in combination, an impression cylinder, printing cylinders movable towards the impression cylinder and away from it, each printing cylinder supported by a shaft, at least two bearings for supporting the shaft, a third bearing, stops on the shaft at or next to the third bearing, bearing cases for receiving the bearing elements of the first-mentioned bearings, said shaft being axially movable in said bearings, and brackets for supporting said cases and provided with a conical seat, the outer surface of said cases being conical to fit said seats.
- 25 8. Multi color sheet intaglio printing machine comprising, in combination, an impression cylinder, printing cylinders movable towards the impression cylinder and away from it, each printing cylinder supported by a shaft, at least two bearings for supporting the shaft, a third bearing, stops on the shaft at or next to the third bearing, bearing cases for receiving the bearing elements of the first-mentioned bearings, said shaft being axially movable in said bearings, and brackets for supporting said cases and provided with a conical seat, the outer surface of said cases being conical to fit said seats, the smallest diameter of the conical seat being greater than the greatest diameter of the printing cylinder.
- 30 9. Multi color sheet intaglio printing machine comprising, in combination, an impression cylinder, printing cylinders movable towards the impression cylinder and away from it, each printing cylinder supported by a shaft, at least two bearings for supporting the shaft, a third bearing, stops on the shaft at or next to the third bearing, a driving wheel on the shaft of the printing cylinder, a finger rigidly connected with the machine frame, a groove in said wheel engaged by said finger, a catch on said wheel, a sleeve around said catch, a second sleeve around said first sleeve, and a driven wheel rigidly connected with the printing cylinder shaft, said driven wheel having a radial slot for receiving the second sleeve.
- 35 10. In a multi-color sheet intaglio printing machine, in combination, an impression cylinder, printing cylinders movable towards the impression cylinder and away from it and having removable shells, a shaft supporting each of said printing cylinders, two bearings for said shaft free of abutments, whereby said shaft may be shifted longitudinally in said bearings, at least one of said bearings being easily removable, the seat of such bearing being larger than the largest diameter of the printing cylinder, and a third bearing for said shaft, said bearing adapted to support said shaft upon assembly or disassembly of the shell.
- 40 11. In a multi-color sheet intaglio printing machine, in combination, an impression cylinder, printing cylinders movable towards the impression cylinder and away from it and having removable shells, a shaft supporting each of said printing cylinders, two bearings for said shaft free of abutments, whereby said shaft may be shifted longitudinally in said bearings, at least one of said bearings being easily removable, the seat of such bearing being larger than the largest diameter of the printing cylinder, a third bearing for said shaft, said bearing adapted to support said shaft upon assembly or disassembly of the shell.
- 45 12. In a multi-color sheet intaglio printing machine, in combination, an impression cylinder, printing cylinders movable towards the impression cylinder and away from it and having removable shells, a shaft supporting each of said printing cylinders, two bearings for said shaft free of abutments, whereby said shaft may be shifted longitudinally in said bearings, at least one of said bearings being easily removable, the seat of such bearing being larger than the largest diameter of the printing cylinder, a third bearing for said shaft, said bearing adapted to support said shaft upon assembly or disassembly of the shell.
- 50 13. In a multi-color sheet intaglio printing machine, in combination, an impression cylinder, printing cylinders movable towards the impression cylinder and away from it and having removable shells, a shaft supporting each of said printing cylinders, two bearings for said shaft free of abutments, whereby said shaft may be shifted longitudinally in said bearings, at least one of said bearings being easily removable, the seat of such bearing being larger than the largest diameter of the printing cylinder, a third bearing for said shaft, said bearing adapted to support said shaft upon assembly or disassembly of the shell.
- 55 14. In a multi-color sheet intaglio printing machine, in combination, an impression cylinder, printing cylinders movable towards the impression cylinder and away from it and having removable shells, a shaft supporting each of said printing cylinders, two bearings for said shaft free of abutments, whereby said shaft may be shifted longitudinally in said bearings, at least one of said bearings being easily removable, the seat of such bearing being larger than the largest diameter of the printing cylinder, a third bearing for said shaft, said bearing adapted to support said shaft upon assembly or disassembly of the shell.
- 60 15. In a multi-color sheet intaglio printing machine, in combination, an impression cylinder, printing cylinders movable towards the impression cylinder and away from it and having removable shells, a shaft supporting each of said printing cylinders, two bearings for said shaft free of abutments, whereby said shaft may be shifted longitudinally in said bearings, at least one of said bearings being easily removable, the seat of such bearing being larger than the largest diameter of the printing cylinder, a third bearing for said shaft, said bearing adapted to support said shaft upon assembly or disassembly of the shell.
- 65 16. In a multi-color sheet intaglio printing machine, in combination, an impression cylinder, printing cylinders movable towards the impression cylinder and away from it and having removable shells, a shaft supporting each of said printing cylinders, two bearings for said shaft free of abutments, whereby said shaft may be shifted longitudinally in said bearings, at least one of said bearings being easily removable, the seat of such bearing being larger than the largest diameter of the printing cylinder, a third bearing for said shaft, said bearing adapted to support said shaft upon assembly or disassembly of the shell.

bearing for said shaft, and means in said third bearing for adjusting said shaft longitudinally, a bearing element of said third bearing being flattened, the flattened portion being adapted to support the shaft upon removal of said easily removable bearing.

ARNOLD EGLI.
